UNITED STATES PATENT OFFICE.

TRUMAN H. ALDRICH, JR., OF BIRMINGHAM, ALABAMA.

CAR-DUMPING APPARATUS.

No. 852,643.

Specification of Letters Patent.

Patented May 7, 1907.

Application filed January 10, 1906. Serial No. 296,407.

To all whom it may concern:

Be it known that I, TRUMAN H. ALDRICH, Jr., a citizen of the United States, residing at Birmingham, in the county of Jefferson and State of Alabama, have invented new and useful Improvements in Car-Dumping Apparatus, of which the following is a specification.

My invention relates to that class of car dumping apparatus in which a revolute structure, carrying a section of track, is provided with means to engage cars as they run upon the said section of track so that they may be tilted as the structure revolves and their contents dumped.

It is one object of my invention to adapt such a dumping apparatus for use with electric traction means to haul the cars in trains, or singly if desired, the revolute structure carrying a section of the electric conductor so that the motor for handling the cars, at all times maintains control of its cars.

It is a further object to provide means for facilitating the weighing in conjunction with the dumping of the cars, one or more scales being arranged on either or both sides of the dump and so disposed that, while one or more cars of a train are being dumped, one or more cars of the train preferably the car next to be dumped is being weighed, and one man can attend to both weighing and dumping.

It is a further object of my invention to adapt the car retaining devices on the revolute structure to engage the wheel hubs of the cars instead of the wheel rims, the purpose of this being to permit the motor wheels, which are of larger size than the car wheels, to clear these devices, which would not be possible were the devices adapted to engage the car wheels without providing moving parts.

My invention also comprises improvements in the details of construction and arrangement of parts, which in their preferred form are disclosed in the accompanying drawings, in which:

Figure 1, is a top plan view of a car dumping apparatus illustrating the revolute structure in section and the adjacent scale, the cars being indicated in dotted lines. Fig. 2, is an end view of a revolute dumping structure in its upright position. Fig. 3, is a similar view showing the car in its tilted position and illustrating the motor cylinder for

operating the revolute structure. Fig. 4, is a side view of a dumping mechanism which is partially broken away, the motor and adjoining car being partially shown to illustrate their relative positions coupled to the car on the dump. Fig. 5, is a plan view of my improved dumping apparatus with scales on each side. Fig. 6, is a detail view in section of the trolley bar movable with the revolute dumping structure together with the contact spring-post. Fig. 7, is a detail view of the trolley bar and its supporting means.

Similar reference numerals refer to similar parts throughout the drawings.

The embodiment of my invention illustrated in the drawings comprises a track formed by the rails 1 which are supported upon a flooring 2 mounted on trestle work or supporting beams of any desired character. This track comprises a movable section formed by the rails 3, which are mounted in a revolute structure and adapted to be moved thereby into alignment with the rails 1. This structure is a cylindrical metallic frame work comprising at each end an annular ring or wheel 4, each of which carries a metallic cross bar 5 riveted thereto and adapted to support the rail sections 3, being suitably braced by the angle irons 6 to give them the requisite strength. The rings 4 are connected by four brace plates 7. These rings rest upon two pairs of wheels 8 and 9 mounted upon shafts 10 supported in suitable bearings 11 connected to cross beams 12 forming part of the main frame work for the dump. The wheels 8 and 9, on each shaft 10, are provided on their outer sides with peripheral flanges 13, which engage the annular tread portions 14 of the rings 4. In this manner the flanges 13 serve to hold the revolute structure between them against longitudinal movement. It will be noted that the periphery of the rings 4, on each side of the annular portion 14, is provided with grooves, one of which receives a rope or cable 15 connected to the piston 16 of a vertically disposed cylinder 17, and the other a rope or cable 18 connected to a suitable counterweight 19, which is partially shown in Fig. 3. These ropes are each connected to studs, not shown, in the several grooves. A piston and counterweight may be thus connected to each of the rings, or the structure may be operated by a single motor and weight which may be con-

ected to both rings or to only one of them. The rails 3, at the center of the revoluble structure, are supported by a cross bar 20, similar to the bar 6 and braced by angle irons 5 21 connected to brace plates 7. A second pair of beams 22 are mounted above the beams 12 and flush with the floor 2. These beams form the ends of the opening in the floor 2 for the reception of revoluble structure and support the ends of the rails 1.

I provide a scale 23, on the platform of which is mounted a second movable section of the track formed by the rails 24. Since I prefer to so dispose the scale with relation to 15 the dumping structure that while one car is being dumped, the next car in the train may be weighed, it will be necessary to provide a short fixed section of track between the rails 24 on the scale, and the rails 3 in the dump. 20 To make this short section of the track of the desired strength and rigidity necessary to stand the hard wear to which it is subjected, I form it by means of bent rails 25. These rails 25 have sections 26 which close the gap 25 between the rails 3 and 24, after which the rails 25 are bent outwardly at an angle of about 45° and then disposed parallel with the rails 24 at the sides of the scale platform 23. The ends of the rails 24, which connect 30 with the rail sections 26, are cut away at an angle corresponding with the angle at which the rails 25 are bent, as seen in Fig. 1. By providing the rails 25 of this length, I am enabled to fasten them to the frame work 35 very securely so that the short sections 26 thereof are as firm as any other portion of the track.

As shown in Fig. 5, I may provide two scales, one on each side of the dumping apparatus, which arrangement will be advantageous where the dump is disposed between two mines connected to a continuous track through the dump, so that trains of loaded cars from one mine may be run straight over 45 the scales and through the dump and continue as empties to the other mine. By this arrangement the trains of cars running in either direction may be weighed and dumped without it being necessary for the motor to 50 pull the train of cars through the dump and then back them over the scale and dump them.

I have illustrated my invention as particularly adapted for electric haulage, the 55 several cars 27 being provided with couplings or hitchings 28 of any desired character, by means of which they may be connected together and to a motor 29, having a trolley pole 30 which takes the current from a trolley 60 wire 31. The trolley wires are supported in any suitable manner and terminate at insulators 32, suitably supported adjacent to each end of the revoluble structure. This structure carries a conductor bar 33

shaped in cross section and suitably connected at each end to insulating blocks 34, bolted or riveted to the rings 4. This bar forms a continuation of the trolley wire 31 when the revoluble structure is in the position in Fig. 2. To connect the bar 33 in circuit 70 with the trolley wires, I lead connections from the wires on each side of the dumping structure to a spring contact plate 35. This spring is connected to an insulating block 36 supported above the structure and is adapted 75 to be engaged by a contact post 37 bolted to the top of bar 33. The spring is preferably very stiff and has but little play so that when the revoluble structure, in dumping a car, has moved the contact post 37 out of engagement therewith, it will not come in contact with any of the plate braces 7 or other parts of the revoluble structure. When the contact post is in engagement with the spring 35, the bar 33 forms a continuation of the trolley wire so that the motor 29 can pull through 80 the revoluble structure, or come to a stop therein, without having its current connections broken.

It will be noted that the wheels 38 of the 85 motor are of considerably larger diameter than wheels 38 of the cars 27. It follows therefore that the means for engaging and holding the cars in fixed relation to the revoluble structure must be such that the 90 wheels for the motor, in its passage through the revoluble structure, will clear such means. These retaining means for the cars comprise angle irons 40 fastened to the inner sides of the rings and to the tops of the bars 6. A 95 brace bar 41 serves to strengthen the connections between these angle irons and the bars 6. Rails 42 are connected to the vertical sides of the irons 40 on each side of the revoluble structure and extend lengthwise there-through in a position to engage hubs 43 for the car wheels. The motor wheels will clear these rails 42, but the latter will engage and firmly hold the car being dumped, as seen in Fig. 3.

It will be noted that the cylinder 17, which may be supplied with air or steam as desired, is disposed above the dumping platform and in a position where it is free from the dust. By thus disposing it, the cylinder can not be 105 struck by pieces of coal or ore, which is often the case when the cylinder is below the dumping platform. Also by disposing the cylinder vertically, guides for the piston rod 110 may be dispensed with.

In operation a train of loaded cars drawn by the motor 29 is brought up to the dump, the movement of the train being arrested for a short period as each car moves on to the 115 weighing platform 23. After the first car has been weighed, it moves on to the revoluble structure as the motor moves off it and as the succeeding car assumes position on the

scale. The motor being clear of the revoluble structure, during the short interval of weighing the second car, air or steam is admitted to the cylinder 17 and the first car is dumped and returned to a vertical position with great rapidity and without being disconnected from either the motor or the car being weighed. The train is then moved forward a sufficient distance to bring the second car onto the revoluble structure and the third car onto the scale. The movement of the train need be arrested only for a very short interval of time as each car is dumped and weighed, it being possible for a skilful operator to dump and weigh all of the cars of a train successively, while they are in slow motion. After a train of cars has been dumped, it may be run back through the dump or continue to a second mine beyond the dump, where, being again loaded they are returned to the dump and weighed on the scale on the side from which they approach the dump. While two scales are not necessary, it avoids the delay attendant upon drawing the train of cars through the dump and then backing them over the scale and dump.

The couplings 28 are such as will permit the tilting of the car, without disconnecting it from the adjacent cars, any ordinary mine car hitching being sufficient for the purposes. By continuing the trolley wire connections through the revoluble structure, it will be seen that the motor is at all times in full control of its train.

To provide for the operation of the dump with great rapidity but without undue strain, I use the following mechanism for controlling the operation of the piston 16. Steam or air is admitted through a pipe 44 to a four-way valve casing 45. A three-way valve 46 is disposed in this casing and acts to throw the ports 47 and 48 into communication with the supply port at 44 or the exhaust port 49. A pipe 50 leads from the port 47 to the lower end of the cylinder, being provided with a check valve 51 which prevents the return flow of pressure through this pipe from the cylinder. The port 48 communicates through a pipe 52 with the side of the cylinder at a predetermined distance from the lower end thereof. A check valve 53 in this pipe prevents the flow of high pressure from the valve casing into the cylinder but permits the pressure from the cylinder to exhaust freely therethrough. A regulating valve 54 in this pipe controls the rapidity of the exhaust of pressure from the cylinder through it. An arm 55, connected to a squared end on the valve 46, is provided with a bifurcated end 56 which straddles the piston rod. A weight 57 at the outer end of this arm substantially balances it so that the valve will remain in any position. An operating rope 58 is connected to this arm

which is so disposed that its end 56 will be engaged and moved by block 59 at the lower end of the piston rod as the piston completes its up stroke.

In operation, when the car is on the dump, the attendant pulls the rope 58 and opens the valve. The pressure rushes in through the pipe 50 and moves the piston upwardly with great rapidity. The up stroke of the piston rod will engage the arm 55 and move the valve so that the ports 47 and 48 are opened to the exhaust. The check valve 51 closes the pipe 50 but the pressure exhausts rapidly through the pipe 52, the piston being drawn down quickly by the action of the counterbalance on the revoluble frame. When the piston passes below the port for the passage 52, it cushions itself, this cushioning effect taking place just before the rails 3 on the dump move into alignment with the main track rails. To positively stop the revoluble structure when the rails are in alignment, I provide a stop 60, connected to the framework and adapted to engage an integral lug 61, formed in one of the grooves of a ring 4. In practice the pipe 52 enters the cylinder at such a point that the cushioning effect does not commence until the end of the return stroke of the piston. This facilitates the speed of operation and it insures against the parts being jarred or injured. It will be noted that the only attention required of the operator is to pull the rope 58 when the car is on the dump.

I have thus described an illustrative embodiment of my invention as is required by the patent statutes, but it will be understood that it is my purpose to cover such modifications and changes as come within the scope of my invention as hereinafter defined in the claims.

What I claim as new and desire to secure by Letters Patent, is:—

1. A car dumping apparatus, comprising a revoluble structure, supports therefor, a train of cars, means to couple said cars together, a track therefor comprising fixed rails and rails movable with said structure, car holding devices carried by said structure, and means to revolve the structure to dump the contents of the car or cars held therein, in combination with a scale to weigh one or more cars of said train while others are being dumped, said scale being disposed with relation to said dumping structure that, as one or more cars are moved into the latter, one or more cars are moved onto the scale, both weighing and dumping operations taking place simultaneously upon cars of the same train while coupled together.

2. A car dumping apparatus, comprising a revoluble structure, fixed track rails, rails carried by said structure and adapted to be moved into alignment with said track rails,

cars, means to couple said cars so they may be moved in a train through said revoluble structure, means carried by said structure to engage and hold the cars, as they move into said structure, in fixed position therein, means to revolve said structure and the car or cars therein, and means to weigh the cars, so disposed relatively to said structure that as one car of the train is being dumped, another car of the same train is being weighed, the cars remaining coupled during both dumping and weighing operations.

3. In a car dumping apparatus, a revoluble structure, a track comprising a section formed by rails movable with said structure, cars, means to couple said cars in a train, electric haulage means for said train of cars comprising a motor, and an electric conductor from which motor derives current and which passes through said revoluble structure, said structure being adapted to dump the contents of the cars successively and without uncoupling them as they take position therein.

4. In a car dumping apparatus, cars, a track therefor, a movable structure carrying a part of said track, means to hold one or more cars in fixed relation therein, an electric motor for moving said cars, a trolley wire from which said motor derives current, and a conductor, movable with said structure, which is in circuit with and forms a part of said trolley wire when said structure is in position to receive and discharge cars.

5. In a car dumping apparatus, a track, a movable structure carrying a part of said track, dump cars having wheels provided with hub projections, an electric motor car adapted to be coupled to said cars, the wheels of said motor car being of greater diameter than those of the dump cars, angle irons connected to said structure, and longitudinal bars supported by said irons in position to clear the motor car wheels and engage the hubs of the dump car wheels to retain said cars in fixed position on said structure as it is moved to dump their contents.

6. In a car dumping apparatus, a track, dump cars thereon, a revoluble structure comprising metallic rings, movable rails forming a portion of said track and car retaining bars supported above said rails, said rails and bars being connected to said rings and acting to brace them together, insulators connected to said rings, a conductor supported by said insulators above the track section in said structure, electric means for moving cars through said structure, trolley wires on each side of said structure, a contact carried by said conductor, and a contact spring in circuit with said trolley wires and adapted to be engaged by said contact on the conductor, substantially as described.

7. In a car dumping and weighing apparatus, a platform, a track for the cars to be han-

dled comprising fixed and movable sections 65 of rails normally disposed in alignment, a movable dumping structure carrying one of the movable track sections, a scale platform carrying the other movable track section, and a fixed track section between said movable sections formed by bent rails, substantially as described.

8. In a car dumping apparatus, a revoluble structure carrying rails, a fixed track, cars movable thereon and adapted to pass 75 onto the rails in said structure, means to couple said cars together, wheels supporting said structure, means to hold the car or cars in said structure as it revolves without uncoupling it or them from the other cars, and means 80 to control the operation of said structure, which comprise a motor disposed above the structure in a position where it is protected from the dust and material dumped, a counterbalance weight disposed below the structure, 85 and flexible connections from said motor and weight to said structure.

9. In a car dumping apparatus, cars, a track therefor, a movable structure carrying a part of said track, means to hold one or 90 more cars in fixed relation to said structure and means to revolve the structure and dump the contents of the car or cars held therein, said means comprising a fluid motor and a counterbalance weight operatively connected 95 to said structure, said motor comprising a cylinder and piston, a three-way valve, and two passages controlled by said valve and entering the cylinder at one end and at the side adjacent to said end, a check valve to prevent the exhaust of pressure through the passage entering the end of the cylinder, a check valve to prevent the admission of pressure to the cylinder through the passage entering its side, means to control the admission of pressure to said cylinder to revolve said structure, and means to trip said three-way valve so that the structure automatically rights itself upon completing its dumping travel.

10. In a car dumping apparatus, the combination with a revoluble structure adapted to receive a car or cars, of a motor for revolving said structure to dump the car or cars therein, comprising a cylinder, a pressure admission port at one end of the cylinder, a pressure exhaust port at the side of the cylinder, valve means to admit pressure to the cylinder through said admission port in one position and to permit the exhaust of pressure therefrom through said exhaust port in another position, a valve to regulate the exhaust, and a piston, connected to said structure, which automatically moves said valve means to exhaust its operating fluid pressure as it completes the dumping movement of said structure, manually controlled means to admit pressure to this cylinder, a counterbalance weight to restore the revoluble struc-

ture to initial position, and a positive stop for said revoluble structure, said exhaust port leading from the cylinder at a point which will cause the piston to cushion and arrest the movement of the revoluble structure just before it rights itself and engages said stop.

In testimony whereof I have hereunto set my hand in presence of two subscribing witnesses.

TRUMAN H. ALDRICH, Jr.
